The ornamental design for an arch for balloons, as shown and described.

DESCRIPTION

FIG. 1 is a perspective view of an arch for balloons, showing my new design;

FIG. 2 is another perspective view thereof;

FIG. 3 is a front elevational view thereof;

FIG. 4 is a rear elevational view thereof;

FIG. 5 is a left side view thereof, the right side view being a mirror image of FIG. 5 and therefore not shown;

FIG. 6 is a top plan view thereof;

FIG. 7 is a bottom plan view thereof;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 1; and,

FIG. 15 is a partial enlarged view of FIG. 1.

The broken lines in FIGS. 1 and 8–15 are for the purpose of annotating the enlargement views only and form no part of the claimed design.
